UNITED STATES PATENT OFFICE.

RUDOLPH MIEHLING, OF NEW YORK, N. Y., ASSIGNOR TO JOHN J. BOTT, OF JERSEY CITY, NEW JERSEY.

MACHINE FOR JOINING THE OVERLAPPING ENDS OF CINEMATOGRAPHIC FILMS.

Application filed April 9, 1921. Serial No. 459,984.

To all whom it may concern:

Be it known that I, RUDOLPH MIEHLING, a citizen of the United States, residing in the borough of Manhattan, city, county, and

5 State of New York, have invented certain new and useful Improvements in a Machine for Joining the Overlapping Ends of Cinematographic Films, of which the following is a specification.

10 My invention relates to that class of machines known in the art of cinematographic films, as "film patching machines" in which the ends of the film overlap to form a patch.

15 I am aware that machines have been constructed whereby the ends of the film after having been cut with scissors by hand, are placed between clamping devices, the emulsion removed from the end or ends of the 20 film, the end or ends of the film then coated with a binding cement by hand, and the two ends of the film then placed one upon the other by hand, in a clamping device and held under pressure.

25 I am also aware that it has been proposed to cut both ends of the film together at one operation, then separate the film, and "butt" the ends together, end for end, and apply a separate cemented strip over the intervening 30 space and unite the two ends under pressure.

35 But these devices are not the equivalent of my invention, which consists broadly in cutting both ends of the film positively and simultaneously a prescribed length, so that when one end is treated with a binding cement, and the ends are brought into contact with each other the overlapped ends will insure a perfect joint of film in all respects, and have the appearance of one continuous length of film; also in so constructing the device that both ends of the film are held positively and independently of each other during the operation of cutting 45 and cementing.

An incidental feature of my invention consists of embodying a scraping device suitably mounted upon the machine and being adapted to be operated by hand for the 50 purpose of removing the emulsion from the film.

The invention also includes minor details

of construction hereinafter more fully described and claimed.

In the accompanying drawings, 55 Figure 1 is a plan of my improved machine;

Fig. 2, a front elevation of the same; Fig. 3, a front elevation, showing the clamping devices raised and in an upright 60 position;

Fig. 4, a side elevation of the machine the parts being in the position shown in Fig. 2;

Fig. 5, a rear elevation thereof; 65 Fig. 6, a horizontal cross section taken upon plane of line 6—6 Fig. 1;

Fig. 7, a sectional detail elevation taken upon plane of line 7—7 Fig. 1, showing the film ends in position; 70

Fig. 8, a partial sectional detail view upon an enlarged scale to more clearly illustrate the parts in the position they assume just prior to the cutting operation;

Fig. 9, a similar view showing the parts 75 in their relation to each other after the ends of the film have been cut;

Fig. 10, a similar view to Fig. 6, upon an enlarged scale to more clearly show the overlapping of the ends of the film; 80

Fig. 11, a partial plan view of the machine, showing a scraper attached to one of the clamps;

Fig. 12, a sectional detail view showing the relation of the scraper with the end of 85 the film;

Fig. 13, a sectional detail elevation upon plane of line 13—13 Fig. 11, the scraper being shown in its relative position with relation to the anvil; 90

Fig. 14, a similar view, the scraper being shown as thrown back out of the way and in the position shown in Fig. 11.

For the purpose of illustration I have shown my improved machine mounted upon 95 a wooden base A, or other suitable material, having the receptacles A', A'', mounted thereon for holding water and binding cement respectively, and in Fig. 1, I have shown a depression A'', in the base A, for 100 holding a scraper or knife S'.

The base b, of the machine, together with its lugs b', b'', b''', and anvil B', is preferably made in one piece, and may be secured to the

wooden base A, by any suitable means as by screws a , a , shown in dotted lines, Figs. 2 and 3.

The upper surface of the anvil B', is provided with teeth b^{22} , b^{22} , for engaging with the sprocket holes f , in the film F.

A pin or shaft C, is mounted in the lugs b' , b^2 , b^3 , one end of which is formed with a screw thread c , which engages with a female screw thread in the lug b' ,—the other end being formed with a head c' .

The clamp D, is mounted upon the pin C, by means of a knuckle d , at its rear end, and rests between the lugs b' , b^2 . This knuckle d , is also formed with a cam surface u' , shown in dotted lines Fig. 3, which bears against a tension leaf spring S, secured to the underside of the anvil B'. The knuckle d , is also formed with a flat bearing surface d^3 , so that when the clamp D, is raised at right angles to the anvil B', it will rest upon the spring S, and be held securely in that position until again brought forward.

The clamp D, is also provided with a handle d^2 , at its front end to facilitate the raising and lowering of the same with relation to the stationary anvil B'.

A movable anvil or platen B², is mounted upon the pin C, between the lugs b^2 , b^3 , the rear end of which is formed with the knuckles d^4 , d^4 , having the cam bearing surfaces d^5 , d^5 , and flat surfaces d^{55} , d^{55} , for the purpose described, and which rest upon the leaf spring S, when the platen D², is raised.

Projecting from the upper side of this movable platen D², are pins or teeth d^6 , d^6 , for engaging in the sprocket holes f , formed in the film F. A handle d^{78} , is provided at the outer end of the platen D², for convenience in raising and lowering the same.

A stop b'' , projecting outward from the inner side of the anvil B', limits the downward movement of the movable platen D².

The clamp D', is mounted upon the pin C, its rear end being formed with a knuckle d' , having a cam bearing surface d^{70} and flat bearing surface d^{71} , which rests upon the leaf spring S when raised,—said knuckle d' , being centered between the knuckles d^4 , d^4 , of the movable platen D². The clamp D', is also provided with a handle d^{71} , at its front end for convenience in raising and lowering the same.

A recess d'' , formed in the outer edge of the clamp D', for the reception of the rock bearing surface arm d^8 , which is pivoted centrally and rocks on the screw stud d^9 , the inner end of which is formed with a screw thread and is fastened by this means to the clamp D'. This recess d'' , is slightly larger than the rocking arm d^8 , so as to allow said arm to rock freely therein, as will be seen by reference to Fig. 7.

The rocking arm d^8 , projects slightly below the lower surface of the clamp D', so

that when the clamp D', is brought forward a sufficient amount of pressure may be exerted upon the film by the spring S.

The lower edge d^{88} , of the rocker arm d^8 , acts as a cutting edge, which together with the cutting edge d^{22} , formed on the lower side of the movable platen D², and the edge B'', formed on the stationary anvil B', together with the edge d^{33} , formed on the upper surface of the clamp D, cut the opposite ends of the film F, in one operation as will be more fully and clearly explained.

The recesses d^8 , d^8 , d^{18} , d^{18} , formed on the undersides of the clamps D, D', fit over the teeth b^{22} , projecting from the upper surface of the stationary anvil B', and the teeth d^6 , on the movable platen D², thereby protecting the same when the parts are brought together.

The operation of the device is as follows: 85

The parts being in the position shown in Fig. 3, of the drawings, one end of the film F, being placed over the teeth d^6 , d^6 , in the exact position in which the patch is to be made, upon the movable platen D², the clamp D', is brought forward into position with relation to the platen D², its inner surface resting firmly upon the film F, and holding the same positively in position by reason of the tension of the spring S, on the cam surfaces of the said clamps. The movable platen D², and clamp D', are then raised together by means of the handles d^{78} , d^{71} , at right angles to the stationary anvil B', and held in this position by reason of their inner flat surfaces d^{55} , d^{71} , bearing and resting upon the spring S. 95

The other end of the film is then placed in the exact position it is desired to be cut upon the teeth b^{22} , b^{22} , on the upper surface of the stationary anvil B', the clamp D, being brought forward by means of its handle d^2 , and resting upon the film F, and holding the same positively in position by reason of the rear end d' , resting upon the spring S. 100

The clamp D', and platen D², are then brought forward and downward together, the knife edge d^{22} , formed on the underside of the platen D², coming in close contact with the upper edge B'', of the anvil B', and acting in conjunction therewith in severing the surplus film F, held between them, and at the same time the knife edge d^{88} , on the rocker arm d^8 , coming in close contact with the upper edge d^{33} , of the clamp D, also

severs the surplus film F, held between the platen D², and the clamp D', the downward movement of the parts being limited by the stop b'' , on the anvil B'. The clamp D' and platen D², are then raised together at right angles to the angle B', one end of the severed film F, being still retained between them. 115

It will thus be seen that only a sufficient surface of the film to be treated is exposed 120

upon the anvil B', the emulsion on the film first being treated with water to soften it, which may be applied by a brush held in the water receptacle A', and then scraped off by means of the scraper S', the side d⁴⁴, of the clamp D, acting as a guiding surface and allowing only the required surface of emulsion being removed. Or as shown in Figs. 11, 12, 13 and 14, the scraper S', mounted on the rod s, supported in the lugs s', s', projecting from the upper side of the clamp D, may be used with like effect, the scraper S', being thrown back out of the way when it is desired to raise the clamp D, or bring the clamp D', forward, as shown in Figs. 11 and 14.

The required amount of emulsion having been removed from one end of the film by means of the scraper S', the binding cement is now applied to that end of the film, by means of a brush held in the receptacle A², for holding the material, the edge d⁴⁴, of the clamp D, again acting as a guiding surface, limiting and preventing the flow of any excess of cement upon the film F.

The clamp D', with its rocker bearing surface d⁹⁸, together with the platen D², is then brought forward and downward until they come in contact with the stop b'', on the anvil B'. The clamps D, D', are then raised and the finished film removed.

It is to be understood that the clamps D, D', and platen D², are always under the tension of the leaf spring S, by reason of their rear ends resting continuously and being in contact with said spring during all the operations of the machine. It will be noted that the clamp designated D' and the platen D² are superimposed one on the other and are movable together or independently, the rocker arm d' serving as a cutter operating in conjunction with the cutting edge of the platen to sever the two ends of the film sections simultaneously.

It will be seen that the rocker bearing surface d⁹⁸, is free to adapt itself to any variations of thickness arising from the placing of a surplus of cement upon the end of the film, or to any unevenness of the ends of the film itself when overlapped, by reason of the said bearing surface being under pressure of the leaf spring S.

It will thus be seen that I provide a machine whereby the ends of the film may be quickly and conveniently patched or matched together, and that the patch so made will be accurate and in alignment, by reason of the ends of the film having been cut and treated to a prescribed distance with relation to each other.

What I claim as my invention and desire to secure by Letters Patent is,

1. A film splicing machine comprising a clamp to hold an end of a film, an anvil acting in conjunction with a platen in the

severance of the film, and a clamp and platen movably mounted to move in unison or independently and adapted to clamp the adjacent end of a film and to sever both ends simultaneously, and a rocker-arm carried by said clamp. 70

2. A film splicing machine comprising a clamp to hold an end of a film, a clamp and platen movably mounted to move in unison or independently and adapted to clamp the adjacent end of a film and to sever both ends simultaneously, and a rocker arm carried by the last-named clamp. 75

3. A film splicing machine comprising a clamp to hold an end of a film, a clamp and platen movably mounted to move in unison or independently and adapted to clamp the adjacent end of a film and to sever both ends simultaneously, a rocker-arm carried by one of said clamps, and an anvil having a portion to expose only sufficient surface of the film to be treated and scraped. 80

4. A film splicing machine comprising a clamp to hold an end of a film, a clamp and platen movably mounted to move in unison or independently and adapted to clamp the adjacent end of a film and to sever both ends simultaneously, a rocker-arm carried by one of said clamps, and resilient means for at all times keeping said clamps and platen under tension. 85

5. A film splicing machine comprising a clamp to hold an end of a film, a clamp and platen movably mounted to move in unison or independently and adapted to clamp the adjacent end of a film and to sever both ends simultaneously, a rocker arm carried by the last-named clamp, and resilient means for at all times keeping said clamps and platen under tension. 95

6. A film joining machine comprising a base, a pair of relatively movable members on said base for pressing a film, one of said members having a cutting edge, and a platen movable with the last-named member and having a cutting edge. 100

7. A film joining machine comprising a base, a pair of relatively movable members on said base for pressing a film, one of said members having a cutting edge, a platen movable with the last-named member and having a cutting edge, and a rocker arm on said last named member. 110

8. A film joining machine comprising a base, a pair of relatively movable members on said base for pressing a film, one of said members having a cutting edge, a platen movable with the last-named member and having a cutting edge, and means to apply cement to a film face. 115

9. A film splicing machine comprising a clamp to hold an end of a film, a clamp and platen movably mounted to move in unison or independently and adapted to 120

- 4
- clamp the adjacent end of a film and to sever both ends simultaneously, an anvil having a portion to expose only sufficient surface of the film to be treated and scraped, 5 and a pivotally-mounted scraper movable into contact with a film on such portion of the anvil.
10. A film joining machine comprising a base, a pair of relatively movable members on said base for pressing a film, one of said members having a cutting edge, a platen movable with the last-named member and having a cutting edge, and a spring for keeping said members under tension.
15. 11. A film joining machine comprising a base, a movable clamp, a second clamp, a platen relatively-movable and also movable simultaneously with said second clamp and a rocking member cooperating with one of 20 said clamps.
12. A film joining machine comprising a base, a movable clamp, a second clamp, a platen relatively-movable and also movable with the said second clamp, a rocking mem-
- ber cooperating with one of said clamps, 25 and means for keeping said clamps and platen under tension.
13. A film joining machine comprising a base, a pair of relatively movable members on said base, for pressing a film, one of said members having a cutting edge, a platen movable with said last-named member and having a cutting edge, and a rocker arm on said last-member, said rocker arm projecting below the lower surface of the said 30 clamp.
14. A film joining machine, comprising a base, a movable clamp, a second clamp, and a platen relatively movable and also movable simultaneously with said second clamp, and 40 a rocking member cooperating with one of said clamps, said second clamp being superimposed upon said platen.

RUDOLPH MIEHLING.
